His Attorney.

UNITED STATES PATENT OFFICE.

PETER MOLE, JR., OF SCHENECTADY, NEW YORK, ASSIGNOR TO GENERAL ELECTRIC COMPANY, A CORPORATION OF NEW YORK.

FEED FOR ARC LAMPS.

Application filed April 30, 1923. Serial No. 635,543.

My invention relates to arc-lamps and in particular to the feeding mechanism thereof. Heretofore arc-lamps and in particular arc-lamps of a high intensity or Beck type, 5 have been made with a step-by-step or discontinuous feed in which a star-wheel is operated periodically. This mechanism is a source of considerable trouble and it is one 10 of the objects of my invention to substitute for this type of feed a more dependable one, and one by means of which the electrode may be fed continuously and without any 15 interruption, thereby insuring a very steady light. It is also an object to provide details of improvement to increase the efficiency of such a device.

Referring to the accompanying drawing, Fig. 1 is a front elevation of the feeding mechanism as applied to a positive electrode; Fig. 2 is an enlargement of a section of the feeding mechanism, Fig. 1. From the drawing it will be seen that the electrodes 2 and 3 are respectively the negative and the positive electrodes. The positive electrode passes through the jaws 4 of the usual electrode holder and extends through the yoke 5 of the frame 6 and through the heads 7 and 7^a of the rotatable cage 8. This cage has a bearing in the yoke 5 and another bearing in the opposite yoke 9 of the frame 6 (see Fig. 2). Through this head 7^a a tube 10 extends, which tube is supported by a second bearing in the yoke 11. On its left end this tube is provided with a gear 12 and on its right end it is provided with a hand-wheel or knob 13 for rotating the tube, and therefore the gear 12, by hand. For the purpose of protection, the knob is insulated from the tube by any suitable insulating covering as for example in the form of a tube 14. The electrode 3 as shown projects into the tube 10 which latter is hollow all the way through. In trimming the lamp a new electrode is inserted through the opening 15 of this tube and thrust through the jaws 4 into position. As shown in Fig. 2, the head 7^a has a sleeve 16^a to which latter gear 16 is locked. It will be seen that this sleeve 16^a extends through the head 7^a. Between the heads 7 and 7^a there is mounted a worm 17 on the right-hand end of which there is a gear 18 which engages with gear 12. To the right of the gear 16 there is provided on the tube 10 a collar 19 which is secured to the tube. To the right of the

yoke 11 there is a collar 20 which is loosely mounted on the tube 10 the surface of which is provided with pins 21 that project to the right. Immediately to the right of the collar 21 there is a third collar 22 which is secured to the tube 10 in any suitable manner. This collar 20 is provided with notches into which the pins 21 project. Near the right end the same collar is provided with threads and a nut 23 therefor. On the outside of the collar 22 there is wound a helical spring 24 which serves as a compression member between the nut 23 and the collar 20.

With the foregoing arrangement it will be seen that by turning the nut 23 the spring 70 is compressed against the collar 20. The result is that the tube 10 is drawn to the right thereby increasing the friction between the collar 19 and the left-hand face of the yoke 11. The object of this tension is to prevent the tube from turning when the cage 8 is being rotated during which operation the gear 18 revolves about the gear 12 which latter is normally stationary. The object 75 of the pins 21 is to enable the necessary lateral movement to take place between the collars 20 and 22 in order that the friction between the collar 19 and the yoke 11 may be regulated. On the other hand, if it becomes necessary to change the adjustment of 80 the electrode 3, the worm 17 which controls this adjustment, as will presently appear, may be rotated by applying sufficient force to the hand-wheel 13. As indicated in Fig. 1, there is in engagement with the gear 90 wheel 16 a worm on the shaft 31, which shaft is driven through the medium of the motor 18^a. Therefore when the motor is in operation, the gear 16 is rotated and therefore the cage 18 is rotated carrying 95 with it the worm 17. The rotation of the cage causes the gear 18 to rotate about the gear 12 thereby causing the rotation of the worm 17 upon its bearings in the heads 7 and 7^a of the cage. As indicated in the 100 drawing, the worm 17 is provided with a nut 25. Riveted to the nut or secured thereto in any suitable manner is a plate 26 that extends transverse the axis of the cage. This plate is provided with an opening 27 through which the electrode passes. Back of the vertical plane through the axis of electrode 3 parallel with the worm 17 and journaled in the heads 7 and 7^a of the cage, 105 there is a rod, not shown. This rod also 110

passes through a hole in the plate 26 and serves as a guide and support for the plate. Therefore, whenever the worm 17 is rotated, the plate 26 travels back and forth along the guide-rod in unison with the nut 25. Projecting to the left from the plate 26 there is a shoulder 28 having a seat which receives the carbon. This shoulder is suitably secured to the plate 26 but is insulated therefrom. For this purpose there is a layer of mica 29 or other suitable insulating medium. This shoulder is provided with a cap 30 which is provided with a seat and which serves as a strap over the carbon. This cap is secured to the shoulder 28 by screws 32, Fig. 1. The electrode 3 is thus clamped to the plate 26 and is forced to travel therewith. It will thus be seen that I provide a constant feed arrangement which carries the electrode 3 forward steadily as long as the motor 18^a is operating. This is accomplished as indicated through the medium of the worm 17 which, in a planetary fashion, rotates about the gear 12 together with the cage 8. Obviously, the electrode 3 also rotates with the cage 8.

If, while the arc is burning, it is found that the electrode 3 is not properly adjusted with respect to the negative electrode 2, the relation between the two electrodes may be changed by the hand-wheel 13 regardless of whether the motor is operating or not. If the motor is operating, the gear 18 is rotating about the gear 12 which is on the end of the tube 10. Obviously, therefore, by rotating the hand-wheel 13, either clockwise or counterclockwise, the rotation of the gear 12 and therefore of the worm 17 can be either accelerated or retarded with the result that the electrode 3 may be either advanced or set back to the desired point. If the motor is not operating and it is desired to move the electrode 3, this can be accomplished by the same operation inasmuch as the connection between the hand-wheel 13 and the worm 17 is independent of the connection between the worm 17 and the motor 18^a.

While I have illustrated my invention in connection with a specific form of apparatus, it will be understood that I do not wish to limit myself exclusively to the construction shown as the disclosure will enable those skilled in the art to carry out my invention through the medium of other modifications which will readily suggest themselves to those skilled in the art.

What I claim as new and desire to secure by Letters Patent of the United States, is—

1. In an arc lamp an electrode, a main gear having its axis coincident with the axis

of the electrode and a satellite gear in engagement with the main gear, a motor for driving the satellite about its axis to feed the electrode longitudinally and at the same time about the axis of the main gear to rotate the electrode, whereby a continuous rotation and feed motion is imparted to the electrode. 65

2. In an arc-light mechanism, an electrode and a planetary gear with a main gear and a satellite gear element, a motor for driving the satellite element, said element being in permanent engagement with the electrode whereby a continuous feed is imparted to the electrode by the motor, means for normally holding the main gear stationary and additional means whereby the main gear may be rotated independently of the motor. 70 75

3. In an electric light mechanism, an electrode, a feed mechanism for the electrode 80 comprising a planetary gear having a main gear element and a satellite gear element, the latter adapted to rotate about the main element, a screw driven by the satellite, and a nut driven by the screw for feeding the 85 electrode, and a motor for driving the satellite about the main element, and means whereby said main element may be rotated thereby causing the rotation of the satellite independently of the motor. 90

4. In an arc lamp, an electrode holder, a frame mounted to rotate on said holder about the axis of the electrode, a main gear mounted concentric with the electrode, an auxiliary gear mounted on said frame to rotate as a satellite about the main gear, said frame locked in engagement with said electrode, said satellite and gear being locked in engagement with the electrode through suitable means and a motor for rotating the 100 frame to cause the electrode to rotate and to travel longitudinally. 95

5. In an arc lamp, an electrode holder, a frame, mounted to rotate on said holder about the axis of the electrode, a main gear mounted concentric with the electrode, an auxiliary gear mounted on said frame to rotate as a satellite about the main gear, said frame locked in engagement with said electrode, said satellite and gear being locked in engagement with the electrode through suitable means, and a motor for rotating the frame to cause the electrode to rotate and to travel longitudinally, and means for rotating the main gear to affect the rate of 110 longitudinal motion of the electrode while the frame is rotating. 115

In witness whereof I have hereunto set my hand this 26th day of April, 1928.

PETER MOLE, JR.
